United States Patent Office

Des. 188,393
Patented July 12, 1960

188,393

CASE FOR A CONTACT SPECTACLE LENS OR SIMILAR ARTICLE

Murray H. Fagan, Boston, Mass., assignor to American Stay Company, Malden, Mass., a corporation of Massachusetts

Filed July 27, 1959, Ser. No. 56,953

Term of patent 14 years

(Cl. D57—1)

Fig. 1.

Fig. 2.

Fig. 3.

Fig. 4.

Fig. 5.

Fig. 1 is a top plan view of a case for a contact spectacle lens shown in closed position, showing my new design;

Fig. 2 is a bottom plan view thereof;

Fig. 3 is a side elevational view thereof;

Fig. 4 is a top plan view thereof; shown in open position; and

Fig. 5 is a vertical cross-sectional view taken on the line 5—5 of Fig. 1.

The side not shown is the same as the side shown.

I claim:

The ornamental design for a case for a contact spectacle lens or similar article, substantially as shown and described.
